UNITED STATES PATENT OFFICE.

LAWRENCE M. JOHNSTON, OF DAYTON, OHIO, ASSIGNOR TO THE NEW ERA GAS ENGINE COMPANY, OF DAYTON, OHIO.

MIXING-BOX FOR GAS-ENGINES.

SPECIFICATION forming part of Letters Patent No. 761,768, dated June 7, 1904.

Application filed June 9, 1902. Serial No. 110,789. (No model.)

To all whom it may concern:

Be it known that I, LAWRENCE M. JOHNSTON, a citizen of the United States, and a resident of Dayton, in the county of Montgomery and State of Ohio, have invented a certain new and useful Mixing-Box for Gas-Engines, of which the following is a full, clear, and exact description, reference being had to the accompanying drawings, which form part of my specification.

My invention relates to improvements in the mixing-boxes of gas-engines, wherein the air is mixed with the gas to form the explosive mixture and by which the mixture is supplied to the cylinders of the engine.

The primary object of my improved mixing-box is to automatically control the supply of gas to the mixing-chamber and to automatically control the supply of the explosive mixture from the mixing-chamber to the engine-cylinders, so that the supply of gas to the mixture and the supply of the mixture to the engine-cylinders shall be always proportional to the work to be done by the engine. In other words, the operation of my mixing-box is such that in connection with a suitable governor it automatically determines at any instant the amount of gas admitted to the mixing-chamber and the amount of the explosive mixture admitted to the cylinders for each explosion, so that when the load is light a small proportion of gas is used in the mixture and a small amount of the mixture is admitted to the cylinders and, on the other hand, when the load is heavy a proportionately larger amount of gas and of the mixture is used, so that at any instant just the right proportion of gas and just the right quantity of the mixture are admitted to the cylinders to produce an explosion of sufficient force to operate the engine under its load at that instant. With the use of my improved mixing-box I am thus enabled to have the explosions occur at regular intervals and not at varying intervals, as is now the general practice, and I find that its use conduces to a high efficiency of the engine with an economical expenditure of gas.

A secondary object of my improved mix-

ing-box is the control by the operator of the supply of air to the mixing-chamber and also the primary control by the operator of the supply of gas to the mixing-box, so that the operator can thus approximately determine in the first instance the relative proportions of air and gas in the explosive mixture. The exact proportion of gas in the mixture, however, as I have before stated, is automatically determined.

The various advantages of my mixing-box will appear more fully as I proceed with my specification.

In the drawings, Figure 1 is a front elevation of my improved mixing-box. Fig. 2 is a top plan view of Fig. 1 with the short pipe at the top removed and with a portion of the outer cap of the mixing-box removed. Fig. 3 is a vertical section on the line 3-3 of Fig. 1. Fig. 4 is a cross-section on the line 4-4 of Fig. 1. Fig. 5 is a rear elevation of the mixing-chamber, showing the ports partially closed. Fig. 6 is an elevation of the inner cylinder of the mixing-chamber.

My improved mixing-box, as shown, consists of a mixing-chamber surrounded at its upper end by a gas-chamber and at its lower end by a mixture-chamber, the first communicating with a source of gas-supply and the latter communicating with the cylinder-heads of the engine. The air is admitted directly into the mixing-chamber, and its supply is under the control of the operator. I also prefer to use a suitable mechanism for controlling the supply of gas to the gas-chamber, this being one of the secondary elements of my invention.

Referring now to the drawings, A is the outer casing, preferably of cylindrical form, which contains the working parts of my improved mixing-box. It has a flat face B at the rear and lugs a, through which pass bolts for attaching it to the cylinder-heads C. A port D in this casing communicates with a similar port D' in the cylinder-heads and serves to admit the explosive mixture to the cylinders. A circular internally-threaded boss D'' at one side of the casing serves for the connection

of the gas-pipe that is to convey the gas-supply. A short cylinder E fits snugly within the upper end of the casing A, so as to be capable of rotation, and rests upon an annular offset E' on the inner face of said casing. This offset divides the casing and serves, in connection with the mixing-chamber, as will appear presently, to form an upper gas-chamber X and a lower mixture-chamber Y, surrounding 5 said mixing-chamber. The cylinder E is provided with a slot E'', which registers vertically with a slot F in the outer casing A in the line of the gas-supply, as best seen in Fig. 4. It has a handle e, which projects through a slot 10 e' in the outer casing A and serves to move the cylinder E so as to make the slot E'' register in its horizontal movement either entirely, partially, or not at all with the slot F, in which latter position, of course, no gas 15 would enter the gas-chamber. Thus by moving the cylinder E the flow of gas into the gas-chamber may be regulated and varied by the operator from nothing to a maximum. The handle e is provided with a needle e'', 20 which travels over a gage on the face of the outer casing and indicates the effective size of the opening through the slots E'' F, so that the operator is enabled to gage the size of the opening and through it the supply of gas to 25 the gas-chamber.

Fitting within the upper end of the casing A is an inner cap G, provided on its upper side with an annular socket in which fits a rotatable disk G'. The bottom of this inner 30 cap and the disk G' are respectively provided with ports g and g', which by the rotation of the disk G' may be caused to register either entirely or only partially with each other. The disk G' has a handle g'', extending through a slot g''' in the cap G, which serves to rotate the disk and in connection with a needle h and a scale over which it travels to regulate and indicate the proportionate size of the effective 35 openings through the ports g g'. An outer cap H fits above the inner cap G and the disk G' and serves to hold the latter in place, the two caps being secured to the casing A in any convenient manner. The cap H has an opening H', usually surmounted by a suitable pipe 40 I for admitting air to the ports g g'. The pipe I, or when it is not used the opening H', is open to the air. The ports g' are preferably made larger than the ports g, so that the admission of air can never be entirely cut off. 45 As will presently appear, these ports are directly above the mixing-chamber and open directly into it.

I have thus far described the arrangement 50 by which the gas and air are respectively admitted into the mixing-box and how the quantity of each may be respectively varied by the operator, so as to approximately determine in the first instance the proportions of the two in the mixture.

65 I have now to describe how the gas is ad-

mitted to the actual mixing-chamber and how the mixture of gas and air is admitted to the cylinders and the means whereby in each case the quantities are automatically controlled and determined by the engine.

70 The mixing-chamber Z consists of an inner and outer cylinder, the one movable upon the other, and, as will be shown, the movement of the slide cylinder is the means through which the effective size of the ports of the 75 mixing-chamber is determined.

J is the outer cylinder and is secured within the casing A, with its upper end bearing against the lower side of the inner cap G and its sides bearing against the annular offset E' 80 on the inner side of the casing A. The parts are so ground at these points as to fit together gas-tight, thus forming the upper and lower chambers X and Y, surrounding the mixing-chamber Z, as above stated. The cylinder J 85 is prolonged below its attachment to the casing A and is screw-threaded on its inner side at the bottom to receive a seat J', provided with a suitable stuffing-box J'', through which passes a rod K. This rod K is secured at its 90 upper end to the bottom K' of the inner cylinder K''. The mixing of the gas and air takes place within this inner cylinder K''. When in its highest or normal position, the cylinder K'' bears against the bottom of the inner cap 95 G, and it is prevented from horizontal rotation by means of a pin 1 and slot 2, the former on the outer cylinder J and the latter on the inner cylinder K'', the slot being open at the top, so as to permit the inner cylinder to 100 be removed.

The inner and outer cylinders are provided with two sets of ports or holes which normally register with each other, of which one set is located opposite the port D in the casing A 105 and the other is opposite the slot F, through which the gas-supply is admitted to the casing A, these ports being marked in the drawings respectively h j and h' j'. A coil-spring 110 l on the rod K bears between the bottom of the cylinder K'' and the top of the seat J', and tends to hold the cylinder K'' in its highest or normal position, with the ports in the two cylinders exactly registering with each other.

The rod K is provided at its lower end with 115 a milled nut M, which is capable of up-and-down adjustment and which is provided with an annular groove in which is pivoted, by means of suitable trunnions, the end of a swinging arm M'. This arm M' is pivoted intermediate its ends to the engine-cylinder and has its other end suitably connected to a slide which is operated up and down by the governor-balls, the arrangement being such that when the balls fly apart on account of the increased rapidity of movement of the engine 120 the arm M is depressed at its connection with the nut M' and is raised when the balls approach each other as the engine slows down. This connection of the arm M' to the slide and 130

operating governor-balls is not shown in the drawings, as it is the usual construction and is readily understood without illustration.

It is apparent that as the arm M' is depressed by reason of the increased speed of the engine (by this is meant a speed above that at which the engine is designed to run under all loads) the rod K , and with it the cylinder K'' , is pulled down, thus causing the ports k k' in the cylinder K'' to register only partially with the ports j j' in the cylinder J , and thereby decreasing the effective size of the ports of the mixing-chamber. If the cylinder be depressed far enough, as when the engine runs away, the ports of the mixing-chamber are entirely closed, thereby cutting off the gas-supply from the mixing-chamber and the supply of the explosive mixture from the engine-cylinders.

From the above it will be readily understood that the rate of flow of gas from the gas-chamber X to the mixing-chamber Z and of the explosive mixture from the mixing-chamber to the mixture-chamber Y and thence through the ports D D' to the engine-cylinders is under the direct control of the governor-balls. Thus when the load is decreased and the engine begins to speed up on account of the smaller load the proportion of gas in the mixture is decreased, and the amount of the mixture supplied to the cylinders is also decreased, and vice versa. In other words, the amount of explosive mixture supplied to the engine-cylinders and the proportion of gas in the mixture at any instant is automatically determined by the engine itself.

To prevent an air-cushion from being formed between the seat J' and the bottom of the cylinder K'' , which would interfere with the easy operation of the movable cylinder, the bottom K' of said cylinder is provided with openings 3.

The amount of air which enters the cylinder K'' is of course, as I have shown, at all times regulated by the operator. The operator also determines the flow of gas into the gas-chamber X , and thus in the first instance approximately determines the relative proportions of the gas and air in the mixture; but the engine itself automatically determines the exact proportions in the mixture and the rate of supply to the engine-cylinders at any instant.

By making the nut M adjustable the proper position of the end of the arm M' may be exactly determined, so as to have the ports of the mixing-chamber fully open when the engine is running at the designed speed under its maximum load. In order to observe the operation of the movable cylinder K'' and see the size of the effective openings of the ports in the mixing-chamber, I prefer to provide the outer casing with a sight or peep hole P , covered by a glass P' . Opposite this I place ports k'' j'' , respectively, in the cylinder K'' and

the cylinder J , having the same relative arrangement and the same size as the other ports in these cylinders. It is thus apparent that the ports will vary just as the others do, so that it is possible to see the effective size of the ports at any instant. The peep-hole P is thus of value in adjusting the parts.

I have thus described the preferred arrangement of my improved mixing-box; but I do not wish to limit myself to the exact construction and arrangement described. It is apparent that the construction may be widely varied without departing from the spirit of my invention. As a single instance of the possible mechanical variations the movable cylinder of the mixing-chamber might be the outer cylinder instead of the inner cylinder, as I have described it, with such mechanical changes as are necessary to bring about its operation in this manner. Other changes of form and arrangement are possible, and I shall not attempt to point them out. Again, it is possible to make use of only portions of my improved mixing-box without adding to it all the details which I have described. These matters will be apparent to a mechanic skilled in the art, and I shall not attempt to discuss them, but shall now point out in the claims what I consider as new in my invention and what I desire to cover by Letters Patent. 95

I claim—

1. In a mixing-box for gas-engines, a mixing-chamber, an air-pipe conveying air thereto, a hand-valve controlling the flow of air from said pipe to said mixing-chamber, a gas-chamber connected to a source of gas-supply, a hand-valve controlling the supply of gas to said gas-chamber, ports connecting said gas and mixing chamber, ports connecting said mixing-chamber with a passage leading to the engine-cylinders, and mechanism whereby the effective size of said ports at any instant is automatically determined by the engine, substantially as and for the purpose described. 100

2. In a mixing-box for gas-engines, a mixing-chamber, an air-chamber located above said mixing-chamber, a partition between said air and mixing chamber provided with ports, a rotatable disk provided with corresponding ports located above said partition and provided with means for rotating it, a gas-chamber connected to a source of gas-supply, and a hand-valve controlling said supply, ports connecting said gas and mixing chamber, ports connecting said mixing-chamber with a passage leading to the engine-cylinders, and mechanism whereby the effective size of said ports at any instant is automatically determined by the engine, substantially as and for the purpose described. 110

3. A mixing-box for gas-engines comprising an outer casing opening into the cylinder-heads at its lower end, and having lugs for securing it to said cylinder-heads, fixed and longitudinally - movable cylinders disposed 120

130

therein, both suitably capped at the bottom and being supported against internally-disposed offsets on the outer casing, one at the middle and one at the bottom, ports in said 5 cylinders connecting the annular chambers thus formed about them with their interior, a rotatable cylinder fitting the internal bore of said outer casing and resting on said middle offset, registerable slots in said rotatable 10 cylinder and said outer casing adjacent a source of gas-supply, a cap resting on the tops of said outer casing and said cylinders, a disk disposed above said cap, said disk and said cap being provided with registerable 15 openings, together with means for automatically depressing said longitudinally-movable cylinder, substantially as described.

4. A mixing-box for gas-engines comprising an outer casing opening into the cylinder- 20 heads with lugs thereon for securing it to said heads, internally-disposed offsets on said casing, one at the middle and one at the bottom, a fixed cylinder screw-threaded to said bottom offset, a longitudinally-movable cylinder with- 25 in said fixed cylinder, and means for automatically depressing the same, each of said cylinders having ports as described and being suitably capped at the bottom; a rotatable cylinder fitting the internal bore of said cas- 30 ing and resting on said middle offset, corre- sponding slots in said rotatable cylinder and in the outer casing adjacent a source of gas- supply, means for rotating said cylinder from the outside of said casing, a false cap closing 35 in said outer casing and said fixed and longitudinally-movable cylinders, an outer cap with a centrally-disposed opening, and a rotatable disk located in a socket in said false cap, said

disk and said false cap having registerable ports, together with means for rotating said 40 disk from the outside, substantially as described.

5. A mixing-box for gas-engines, comprising an outer casing opening into the cylinder-heads with lugs thereon for securing it to said heads, internally-disposed offsets on said casing, one at the middle and one at the bottom, a fixed cylinder provided with a screw-cap at the bottom and being screw-threaded to said bottom offset and fitting gas-tight within said 50 middle offset, a longitudinally-movable cylinder within said fixed cylinder having a cap at the bottom provided with the openings 3, an operating-rod secured to said bottom cap and projecting through the bottom of said 55 fixed cylinder, the spring 7 between said bottom caps, registerable ports in said fixed and movable cylinders above and below said middle offset of the outer casing, a rotatable cylinder fitting the internal bore of the outer 60 casing, and resting on the middle offset, with means for operating the same from without, registerable slots in said rotatable cylinder and the outer casing adjacent a source of gas- supply, an inner cap closing in all said cylinders and having a centrally-disposed socket, a rotatable disk in said socket with means for operating the same from without, registerable ports in said disk and said inner cap and an outer cap, having a centrally-displaced 65 opening, substantially as described.

LAWRENCE M. JOHNSTON.
